UNITED STATES PATENT OFFICE.

JOHN DAY, OF BROOKLYN, NEW YORK.

CURTAIN-PIN.

SPECIFICATION forming part of Letters Patent No. 275,160, dated April 3, 1883.

Application filed November 20, 1882. (No model.)

To all whom it may concern:

Be it known that I, JOHN DAY, of Brooklyn, in the county of Kings and State of New York, have invented an Improvement in Curtain-Pins, of which the following is a specification.

Curtain-pins have been made with an ornamental head and screw-shank. My improvement is for the purpose of strengthening the shank of the curtain-pin without increasing the cost.

In the drawings, Figure 1 is a section longitudinally of the curtain-pin. Fig. 2 is a cross-section at *x x*, and Fig. 3 is a plan of the back plate.

15 Ornamental heads for picture-nails and curtain-loops have been made with a head of glass, similar to the ornament *a*, and with a rim, *b*, around the same, by which the ornamental surface is attached to the back plate, *c*. This 20 feature in itself I do not therefore claim. I prefer to employ a back plate, *c*, of heavy sheet-iron, and either enamel the back surface or else introduce a plate, *e*, of thin japanned iron or other smooth sheet metal.

25 The stem *f* of the curtain-pin is made with a screw, *i*, at one end, and the other end is reduced to fit a square or polygonal hole in the back plate, *c*, and the end of the stem is riveted up. In stems for curtain-pins it has been 30 usual to make a flange upon the stem itself,

so as to form a base to screw against the wood-work of the window-frame. This renders the stem expensive, and it is easily bent.

I make use of the wooden shank *h*, that is hollow for the screw-stem to pass through and the surface is turned with ornamental moldings and coves. I also prefer to make use of a feather, *l*, upon the stem, entering a slot in the shank, or to use some other device that connects the shank and screw-stem, so that 40 they are turned with and by the shank in screwing the curtain-pin into the window-casing. This shank serves to stiffen the stem, and, being clamped between the back plate of the head and the window-casing, it forms a 45 very firm and strong stem for the curtain-pin, and improves the appearance of the article.

I claim as my invention—

The improved curtain-pin comprehending the ornamental head *a*, the metal back plate, 50 *c*, the clamping-rim *b*, the screw-stem *f*, riveted at one end to the metal back-plate, and the hollow ornamental shank surrounding the screw-stem, substantially as set forth.

Signed by me this 17th day of November, 55
A. D. 1882.

JOHN DAY.
